UNITED STATES PATENT OFFICE.

CHARLES F. TESTMAN, OF PORTLAND, OREGON.

IMPROVED GOLD-SEPARATOR.

Specification forming part of Letters Patent No. **56,636**, dated July 24, 1866.

To all whom it may concern:

Be it known that I, CHARLES F. TESTMAN, of the city of Portland, in the county of Multnomah and State of Oregon, have invented a new and useful Machine for Separating Gold-Dust from Dirt and Gravel without Water; and I hereby declare that the following is a full, clear, and exact description of the construction and operation of the same, reference being had to the annexed drawings, making a part of this specification, in which—

Figure 1 is a perspective view; Fig. 2, a longitudinal elevation; Fig. 3, a transverse section.

First construct an air-tight room or chamber twenty-four feet square and thirty feet high, and in the center of this air-tight chamber build an oven and fire-place seven feet square and seven feet high, in which can be built the fire *e*. Place two boxes, *a a*, on either side of the fire-place, constructed of wood and lined with sheet-iron, one foot deep, six feet wide, and thirty feet long. The boxes *a a* have a longitudinal elevation or inclination of thirty-five degrees, and also a transverse or lateral elevation or inclination of twenty degrees.

Upon the boxes *a a* are constructed the perpendicular boxes *b b*, one foot deep, six feet wide, and extending from the top of the boxes *a a* to the top of the structure *c c*, in length as the aforesaid elevations will permit and require, and the boxes *b b* empty their contents into the boxes *a a*.

Eight inches between the boxes *b b* are left the open spaces *y y*, to admit the hot air from the oven *e*.

On the top of the boxes *b b* are constructed railroads *c c*, to convey the dirt from the mountain to the boxes *b b*, and if the nature of the mining claim requires it the railroad *d d* will convey the dirt from the tunnel *w*.

f is a door, and the only place that will admit air from without.

g g are stop-cocks to the boxes *a a*, which being opened and shut at pleasure, will control the flow of dry dirt from the boxes *a a*.

h h is a stationary sieve, through which dirt and gravel one inch in diameter will pass freely

to *l*. When *h* is half-full of dirt and gravel, which cannot pass through it to *l*, then turn the termini of the boxes *a a* (see Fig. 2) back against the front of the house and tip the contents of *h* into the sluice-box *x*.

l is the roller-gage, through which the dirt and gravel pass to be ground up by the rollers *m* and *n*, then into *p*, in the bottom of which (see Fig. 2) are ripples one-half inch deep and one-half inch apart, over which the dirt passes into a series of amalgamating-pans, in the bottom of which are placed the quicksilver-pockets *s s*, filled with quicksilver one inch deep, in which revolves the amalgamating-stirrer *q q*, dipping into the quicksilver about three-tenths of an inch.

The spring *v* is attached to the bottom of the sluice *p x*, and by its contact with the stationary roller *n* the sluice *p x* is continually shaken up and down, which motion causes the dirt and gravel to be conveyed through the series of amalgamating-pans out through *t*. The coarser gravel, that cannot pass the bottom of *x*, is carried by the continual shaking of the sluice-box *p x* over *x* and out at *n*.

At *t* is a pocket three inches deep to catch the fine gold-dust that may pass through the amalgamating-pans, if any.

i is a rake, to be used by a tender standing in front of *h* on a platform.

The roller *m* has the spring *o o* attached to each end, which permits the flint-stones one inch in diameter to pass through into *p* if they cannot be crushed by the rollers *m* and *n*.

What I claim as my invention, and desire to obtain and secure by Letters Patent, is—

1. The process of drying dirt in the boxes *a a* and *b b* by means of the fire *e*.

2. The application of the springs *o o* to the roller *m*.

3. The method of constructing the amalgamating-pans *r r*, and procuring thereof the gold-dust in the quicksilver-pockets by means of the continued revolution of the stirrer *q q*.

CHARLES F. TESTMAN.
